UNITED STATES PATENT OFFICE

118,315

DESIGN FOR A DRESS

Sidney Wellins, New York, N. Y.

Application November 9, 1939, Serial No. 88,145

Term of patent 3½ years

To whom it may concern:

Be it known that I, Sidney Wellins, a citizen of the United States, residing at New York, in the county of Queens and State of New York, have invented a new, original, and ornamental Design for a Dress, of which the following is a specification, reference being had to the accompanying drawing, forming part thereof, wherein—

Fig. 2 is a back view thereof.

The characteristic feature of my design resides in the combination on the dress disclosed of the specific blouse member which is tucked and stitched as shown.

I claim:

The ornamental design for a dress, substantially as shown and described.

SIDNEY WELLINS.
